US0D1070052S

(12) **United States Design Patent** (10) **Patent No.:** **US D1,070,052 S**
(45) **Date of Patent:** **** Apr. 8, 2025**

(54) **AROMATHERAPY DIFFUSER**

(71) Applicant: **Yijian (Shenzhen) Design Co., Ltd.**,
Shenzhen (CN)

(72) Inventors: **Wenqin Zhao**, Shenzhen (CN);
Longzhen Qiu, Shenzhen (CN);
Zhenneng Liang, Shenzhen (CN);
Xiaochun Chen, Shenzhen (CN);
Guangxing Gu, Shenzhen (CN); **Zanyu Chen**, Shenzhen (CN)

(73) Assignee: **Yijian (Shenzhen) Design Co., Ltd.**,
Shenzhen (CN)

(**) Term: **15 Years**

(21) Appl. No.: **29/971,601**

(22) Filed: **Nov. 5, 2024**

(51) LOC (15) Cl. **23-04**

(52) U.S. Cl.

(57) **CLAIM**

The ornamental design for an aromatherapy diffuser, as shown and described.

DESCRIPTION

FIG. 1 is a front perspective view of an aromatherapy diffuser, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the aromatherapy diffuser, which form no part of the claimed design.

1 Claim, 8 Drawing Sheets
